Primary Examiner—Martie Thompson*Attorney, Agent, or Firm*—John Gugliorra[57] CLAIM

The ornamental design for a combined desk set and business card holder, as shown and described.

DESCRIPTION

FIG. 1 is a front, left perspective view of a combined desk set and business card holder showing my new design; FIG. 2 is a front elevational view thereof; FIG. 3 is a rear elevational view thereof; FIG. 4 is a left side elevational view thereof; and, FIG. 5 is a right side view thereof.

The dashed line represents a business card for use with the present design, and forms no part of the claimed invention.
